UNITED STATES PATENT OFFICE

2,592,508

ELECTRICAL PRECIPITATOR

Joseph Phyl, Fanwood, N. J., assignor to Research Corporation, New York, N. Y., a corporation of New York

Application February 10, 1950, Serial No. 143,509

7 Claims. (Cl. 183—7)

1

This invention relates to electrical precipitation apparatus for the separation of suspended materials from gases.

More particularly the invention relates to collecting electrodes for use in electrical precipitators in which the suspended material is precipitated in liquid, or semi-solid form, for example, in the collection of tar particles and sulfuric acid mist, and in the wet type of electrical precipitators in which solid particles are collected in the form of a sludge or are flushed from the collecting electrodes by a liquid. A hopper or collecting pan is generally provided at the bottom of the precipitator to collect the precipitated liquid, semi-solid or sludge as it drips off the lower edges of the collecting electrodes.

For maximum efficiency electrical precipitators should be operated with the electrical potential between the discharge and collecting electrodes just below the arcing point. It has been found however that the maximum potential between the discharge and collecting electrodes must be materially lowered to prevent arcing and corona discharge of reverse polarity from the places where the collected material drips from the collecting electrodes in the above mentioned types of precipitators.

A principal object of the invention is to provide collecting electrodes having means for directing the flow of the liquid, semi-solids or sludge, at the bottom of the electrodes to substantially reduce the possibility of back corona discharge and arcing at the drip point, thus permitting the electrical precipitation apparatus to be operated at a higher potential than heretofore possible and thereby substantially increasing the efficiency of the apparatus.

For the purpose of illustration the invention will be more particularly described as applied to an electrical precipitator for cleaning hot tar-containing gases, with reference to the accompanying drawings in which:

Fig. 1 is a vertical section of a vertical flow precipitator employing square pipe collecting electrodes constructed in accordance with the principles of the invention;

Fig. 2 is a sectional view of line 2—2 of the precipitator shown in Fig. 1 of the drawings;

Fig. 3 is an enlarged fragmentary view of a square pipe electrode having modified drip points;

Fig. 4 is an enlarged fragmentary view of a hexagonal pipe collecting electrode constructed in accordance with the principles of the invention;

Fig. 5 is a diagrammatic vertical section of a horizontal flow precipitator employing plate type collecting electrodes embodying the principles of the invention; and

5 Fig. 6 is a fragmentary section on line 6—6 of Fig. 5.

Referring to the drawings and in particular to Figs. 1, 2 and 3, 10 is the shell or casing of the precipitator having a gas inlet 11 and outlet 12. 10 Within the casing discharge electrodes 13 are shown suspended from a support 14, and passing vertically through the centers of square pipe collecting electrodes 15. A retaining frame 16 is shown at the lower ends of electrodes 13 to secure them from lateral displacement and from swinging from side to side in the gas stream. The precipitated tar is collected in the bottom of the precipitator and is withdrawn through drain 17.

20 The lower edges of the collecting electrodes are provided with serratures, as more clearly shown in Fig. 3 of the drawings. Points 18 of the serrated electrodes are at the corners of the square pipes and thus provide drip points at the furthest 25 points from the centrally located discharge electrodes 13.

In operation hot tar-laden gases, enter the precipitator through gas inlet 11, and flow upwardly through the square pipe collecting electrodes, 30 wherein the tar particles become ionized and are precipitated upon the inner surfaces of the collecting electrodes. The precipitated tar flows down the electrodes and is directed by the serrated edges 18 to the drip points 19 at the corners 35 of the square pipes. With the drip points located at the corners of the collecting electrodes, the points furthest from the discharge electrodes, the possibility of arcing at the drip points is substantially reduced.

40 The drip points shown on the electrode illustrated in Fig. 3 of the drawings are provided with smoothly rounded projections 20 having spherically shaped bases, to further reduce the tendency toward back-corona and arc overs at the 45 drip points by eliminating the sharp points of the serrated electrodes.

In Fig. 4 of the drawings a hexagonal collecting electrode 21 is shown constructed with a serrated lower end. The drip points 19 are positioned at the corners of the polygonal tubes electrode at the points of greatest distance from the centrally located discharge electrode 13.

With reference to Figs. 5 and 6 of the drawing it will be seen that the principles of the invention 55 are equally adaptable for use on precipitators em-

ploying plate type electrodes, and on precipitators operating with a horizontal gas flow. In the illustrative embodiments shown in Figs. 5 and 6, 10' is the shell of a horizontal gas flow precipitator having a gas inlet and outlet 11' and 12' respectively. Within the precipitator are discharge electrodes 13' suspended between the plate type collecting electrodes 15', the lower edges of which are serrated in accordance with the principles of the invention to provide drip points 19' located at a greater distance from the discharge electrodes 13' than the perpendicular distance between the discharge and collecting electrodes.

From the foregoing description it will be seen that the present invention provides a method of constructing collecting electrodes for use in electrical precipitation apparatus in which the suspended material is precipitated in liquid, or semi-solid form and in the wet type of electrical precipitators in which solid particles are collected in the form of a sludge or are flushed from the collecting electrodes by a liquid, whereby the aims, objects and advantages of the invention are fully accomplished.

It will be evident that various modifications may be made in the construction of the device and in the form and number of drip points. For example, the lower ends of the collecting electrodes may be scalloped instead of serrated to lessen the possibility of arc over at the drip points.

I claim:

1. In an electrical precipitator for separating suspended materials from gases comprising spaced substantially vertical discharge electrodes, and parallel collecting electrodes adjacent said discharge electrodes, means at the lower ends of the collecting electrodes directing the flow of precipitated liquids, semi-solids and sludge to drip points remote from the discharge electrodes, whereby discharges at the drip points are substantially reduced.

2. In an electrical precipitator for separating suspended materials from gases comprising spaced substantially vertical discharge electrodes, and parallel collecting electrodes, as defined in claim 1, wherein the means directing the flow of precipitated liquids, semi-solids, and sludge to drip points, comprise serratures at the lower ends of the collecting electrodes.

3. In an electrical precipitator for separating suspended materials from gases comprising substantially vertical polygonal tube collecting electrodes and substantially vertical discharge electrodes within said tubular collecting electrodes, serratures at the lower ends of the collecting electrodes directing the flow of precipitated liquids, semi-solids and sludge to drip points at the lower corners of the collecting electrodes, whereby dis-

charges at the drip points are substantially reduced.

4. In an electrical precipitator for separating suspended materials from gases as defined in claim 3, smoothly rounded members projecting downwardly from the drip points of the collecting electrodes.

5. In an electrical precipitator for separating suspended materials from gases comprising substantially vertical square tube collecting electrodes and substantially vertical discharge electrodes within said tubular collecting electrodes, serratures at the lower ends of the collecting electrodes directing the flow of precipitated liquids, semi-solids, and sludge to drip points at the lower corners of the collecting electrodes, whereby discharges at the drip points are substantially reduced.

10 6. In an electrical precipitator for separating suspended materials from gases comprising spaced substantially vertical discharge electrodes and parallel plate collecting electrodes adjacent said discharge electrodes, serratures along the lower edges of said plate electrodes directing the flow of precipitated liquids, semi-solids, and sludge to drip points remote from the discharge electrodes, whereby discharges at the drip points are substantially reduced.

15 7. In an electrical precipitator for separating suspended materials from gases comprising spaced substantially vertical discharge electrodes and parallel plate collecting electrodes adjacent said discharge electrodes, means directing the flow of precipitated liquids, semi-solids and sludge to drip points positioned along the lower edges of the plate collecting electrodes between the spaced discharge electrodes to substantially reduce discharges at the drip points, said directing means comprising serratures along the lower edges of said plate electrodes.

40 JOSEPH PHYL.
